[57] CLAIM

The ornamental design for a front panel for an expansion processor controller for a data processing system, as shown and described.

DESCRIPTION

FIG. 1 is a front elevational view of a front panel for an expansion processor controller for a data processing system showing my new design;

FIG. 2 is a right side elevational view thereof, the left side elevational view being identical; and,

FIG. 3 is a top plan view thereof.

The rear elevational view is unornamented.

FIG. 3

FIG. 1

FIG. 2
